OXIDATION OF STEROIDS BY MYCOBACTERIA

Gilbert M. Shull, Huntington Station, and Donald A. Kita, Jackson Heights, N.Y., assignors to Chas. Pfizer & Co., Inc., New York, N.Y., a corporation of Delaware

No Drawing. Application July 27, 1955
Serial No. 524,817

12 Claims. (Cl. 195—51)

This invention is concerned with the oxidation of certain steroid compounds by microbiological means. In particular, it is concerned with the oxidation of certain 3-keto-4-unsaturated steroid compounds by means of certain microorganisms or oxidizing enzymes produced by these microorganisms.

This application is a continuation in part of applications Serial Number 431,619, filed May 21, 1954; Serial Number 483,842, filed January 24, 1955; and Serial Number 484,828, filed January 28, 1955, by Gilbert M. Shull et al. It is also a continuation-in-part of application Serial No. 276,678, filed March 14, 1952, and now abandoned.

As is disclosed in the above mentioned applications, by subjecting a 3-keto-4-unsaturated steroid compound to the action of a species of the genus *Mycobacterium*, there is produced a compound which is a 3-keto-1,4-unsaturated steroid. Some nuclear oxygenation also takes place, chiefly in the 14 position when this position is available. The main product of the oxidation, however, is the dehydrogenation product. It is thus possible by the use of organisms of the genus *Mycobacterium* to produce compounds having a 3-keto group and unsaturated at the 1 and 4 positions. Certain compounds of this type are extremely valuable because of their biological activity, and it is therefore of great value to have a simple, one step method of dehydrogenation at the 1,2 positions.

This invention is the first case in which dehydrogenation in the A ring of a steroid has been produced by the use of microorganisms without the simultaneous oxidative cleavage of a side chain present in the 17 position. This invention is also the first instance in which an organism of the genus *Mycobacterium* has been used in a commercial chemical reaction and is indeed believed to be the first time that any use has been found for organisms of the family *Mycobacteriaceae*.

It has now been found that on contacting a 3-keto-4-unsaturated steroid compound with the oxidizing activity of a species of the genus *Mycobacterium* there is produced oxidation of the steroid compound. The chief chemical reaction is one of dehydrogenation in the 1,2 positions, thereby producing a double bond between these positions. Some oxygenation also occurs at the same time, chiefly in the 14 position when this position is available. The term nuclear oxidation includes both dehydrogenation and oxygenation. It is possible that sometimes both types of oxidation, i.e. dehydrogenation and oxygenation, occur in the same molecule, but this is not generally the case to a large extent. The process of this invention, i.e. the contacting of a suitable steroid compound with the oxidizing activity of a species of the genus *Mycobacterium*, may be carried out by bringing the chosen steroid compound in aqueous solution or suspension into contact with either an actively growing culture of *Mycobacterium*, with cells of *Mycobacterium* removed from the growing culture and suspended in a suitable medium, or by contacting the steroid with extracts of oxidizing enzymes obtained from the culture of a species of the genus *Mycobacterium*.

2

An object of this invention is a process for the preparation of oxidized steroids, particularly 3-keto- $\Delta^{1,4}$ steroids, from the corresponding 3-keto-4-unsaturated compounds. A further object of this invention is an economical process for this dehydrogenation reaction which may be readily scaled up for large volume production. Further objects of this invention will be apparent from the following discussion.

A variety of 3-keto-4-unsaturated steroid compounds may be used as starting materials for the reactions of this invention. These include such materials as:

Compound F (hydrocortisone)	9 α -fluoro-Compound F
Compound E (cortisone)	14 α -hydroxy-Compound F
Corticosterone	11 α -epi-hydrocortisone
Compound S	$\Delta^{4,6}$ -androstadienone
14 α -hydroxy-Compound S	11 β ,17 α -dihydroxyprogesterone
Desoxycorticosterone	Δ^{14} -dehydro-Compound S
Androstanedione	Testosterone
19-nortestosterone	Progesterone
17 α -hydroxyprogesterone	16-dehydroprogesterone
11-ketoprogestrone	A9(11)-dehydro-Compound S

In general this process is most applicable to 3-keto- Δ^4 steroid compounds having from 18 to 21 atoms in the carbon skeleton. The products of the reaction may be detected by careful comparison of paper chromatograms of the products formed by the reaction of this invention with known steroid compounds. This method has been tested on a variety of compounds and is known to give reliable results. Reports of this method are available in the chemical literature.

In carrying out this invention various species of the genus *Mycobacterium* may be used for bringing about oxidation of the steroid nucleus. These are available from public culture collections, for example the American Type Culture Collection of Washington, D.C. These include known species such as *Mycobacterium* species 607, *M. berolinense*, *M. lacticola*, *M. thamnopheos*, and the species *M. smegmatis* ATCC 101. Particularly useful are organisms of the species *M. phlei*, a living culture of which has been deposited with the American Type Culture Collection of Washington, D.C., where it has

been given the number ATCC 354. The various species of *Mycobacterium* vary considerably in the speed and ease with which dehydrogenation is produced by the cells of the organisms or by products formed during their growth. We have found that certain strains of *M. phlei* and *M. smegmatis* are particularly active in bringing about the reaction of this invention. The various mycobacteria vary somewhat in their requirements for nutritional media. By a minimum of single testing, however, it is possible to determine the composition of suitable media, as well as the optimum conditions for operation, such as pH, rate of aeration, rate of stirring and so forth. In a like manner, the optimum conditions for the dehydrogenation of a particular steroid may be found.

There are several procedures which may be used in the dehydrogenation of steroid compounds according to this invention. In the first of these, nutrient media are seeded from slants of the selected *Mycobacterium*. Such a medium may consist, for instance, of a mixture of a standard bacteriological nutrient broth base, together with glycerol.

It has been found that a neutral, surface-active agent, such as a polyoxyethylene derivative of a sugar alcohol-fatty acid ester (e.g. Tween 80), when added in a minor proportion to the medium, is helpful. The addition of the amino acid asparagine is also helpful. The cultivation of mycobacteria has been described in considerable detail in many publications. The seeded, sterile, nutrient solutions may be grown in shake flasks for two to three days to provide inoculum for larger vessels, and in turn, the larger, stirred, aerated vessels may be used for the inoculation of full production-scale vessels for submerged fermentation. The same medium of the type described above may be used for the large-scale

oxidation of steroids according to this invention. Considerable variation may, of course, be made in the medium. In general there is required a carbohydrate, a source of organic nitrogen, mineral salts and various trace metals.

As pointed out above, rather than conducting the oxidation of the selected steroid compound in the presence of the whole fermentation product, cells may be removed from growing cultures and these may be resuspended in a medium which has been designated the enzyme reaction mixture. Such a reaction mixture may consist, for instance, of a solution which is 0.01 molar in sodium fumarate or other hydrogen acceptor and in magnesium sulfate and 0.03 molar in sodium citrate. It has been found that the presence of a certain amount of adenosine triphosphate, e.g. 0.125%, is also quite useful. Centrifuged, washed cells of the chosen *Mycobacterium* may be suspended in this type of reaction mixture, which is adjusted to a pH of about 6, for example with citric acid. After addition of the steroid compound which it is desired to oxidize, the mixture may be incubated at about 37° C., and samples may be removed from time to time to determine the point at which maximum conversion of the steroid has taken place. In general, this occurs after about one to several days. We have found that the cells from about 100 milliliters of the stirred, aerated mycobacteria cultures may be suspended in about 20 milliliters of an enzyme reaction mixture for suitable results. Considerable variation may be made in these proportions. The steroid compound may be used in a proportion of about 25 to about 200 milligrams/100 milliliters of the enzyme reaction mixture. The compound in solid form is merely added to the medium after adjustment of the pH. The flasks are stoppered with cotton so that they are exposed to the air during the incubation. We prefer to use a small volume compared to the volume of flask, for instance, 20 milliliters in a 125-milliliter Erlenmeyer flask. Alternatively, the mixture may be stirred and aerated. In general, at least a hydrogen acceptor, a divalent metal particularly magnesium, and a buffer are required in the medium.

Rather than removing the *Mycobacterium* cells and carrying out the reaction of this invention in an enzyme reaction mixture, the steroid compound may be added directly to a sterilized portion of nutrient medium, such as is described above, and the medium is then seeded with the chosen mycobacteria. Approximately the same proportion of chosen steroid compound may be used in this case also. Samples of the agitated, aerated mixture may be removed at intervals for determination of the conversion of the steroid compound to the oxidized products. The mixture is maintained at between 25°-37° C. or higher during the growth of the cells and the conversion of the steroid. In general, about two to seven days is required for maximum production of the oxidized compounds. Alternatively, the growth of the cells may be established before addition of the steroid.

A third method which is also very useful for the oxidation of the selected steroid compounds involves the use of oxidizing enzymes produced by the mycobacteria. These may be prepared by a variety of methods from the cells of the chosen organisms. These materials may be released from the cells by several different procedures. These include grinding, particularly with abrasive materials such as powdered glass or sand, which serves to break the cell walls and release the essential materials. A second method is by autolysis. The cells may be removed from the medium in which they are grown. They are then washed and suspended in water. The water may be covered with a thin layer of toluene to prevent contamination, and the mixture is allowed to stand at a temperature of from about 20° to about 50° C. The cells disintegrate within one to several days and the cell residue may be removed by filtration, for instance through a Seitz filter or through a sintered glass bacterial filter. A third method for preparing cell-free elaboration prod-

ucts of the mycobacteria useful for the reactions of this invention is by repeated, rapid freezing and thawing of the cellular material. Another method is by the use of ultrasonic energy to rupture the cells. One further method of use for the same purpose is by the use of a water-miscible solvent and, in particular, acetone. The cells, when placed in such a solvent, are ruptured and an extract of the desired enzymes is obtained. The mycobacteria enzymes may be used for the oxidation of 3-keto-4-unsaturated steroid compounds in media similar to those used with the grown cells, that is, one containing a hydrogen acceptor such as fumarate, a buffer and, in some cases, a bivalent metal, particularly magnesium, as well as a minor proportion of adenosine triphosphate. The cell-free oxidizing enzymes of mycobacteria may be used in media indicated above at a temperature of about 20° to about 40° C. In general, the oxidation of the desired steroid compounds is brought about in a period of from a few hours to several days. The optimum time and temperature and other conditions may readily be determined by a minimum of experimentation. Detailed descriptions of suitable media for both the use of isolated, resuspended cells and of cell-free elaboration products are given in the textbooks "Manometric Technique in Tissue Metabolism," by W. W. Umbreit et al., Burgess Publishing Company, Minneapolis (1949), and "Respiratory Enzymes," by H. Lardy, Burgess Publishing Company, Minneapolis (1949).

The most convenient method for following the course of the oxidation reaction is by means of paper chromatography. Other methods may also be used for this purpose as noted above. In the paper chromatography method, alumina impregnated filter paper is prepared by dipping large sheets of the paper (Whatman No. 54-27" x 22½" sheets—filter paper is particularly useful) in an aluminum sulfate solution (13 grams/100 milliliters). The paper is drained, exposed to an atmosphere of ammonia for 15 hours and the sheets are then washed continuously for six hours with tap water. The sheets are then drained, ironed at a moderate temperature to obtain a flat surface, and are stored at room temperature for 24 hours prior to use. Various solvent systems are used in the development of the paper chromatograms. These have been designated as follows:

45 System I—Hexane
System II—Hexane-ether (19 volumes to 1 volume)
System III—Hexane-ether (16 volumes to 1 volume)
System IV—Ether

50 Five microliter quantities of solutions containing the steroids are placed on the paper along a line three centimeters from one edge of the paper and the spots are spaced two centimeters apart. The edge of each paper is stapled to the opposite edge to form cylinders and each paper is placed in a glass jar of appropriate size. They 55 are exposed to the vapors of the solvent system for one hour at 4-8° C. The jars are then covered with transparent plastic lids, which are sealed with high vacuum silicone grease after sufficient solvent has been placed in the bottom of the jar. The solvent is carried up the paper by capillarity and, in passing the spots where the steroids have been deposited, the various components of these products are moved up the paper at a greater or lesser rate depending upon the structure of the individual compound. The development of the sheets is carried out in a cold room at about 4-8° C. until the solvent front reaches a point about eight centimeters from the top of the paper sheet. This generally takes about four to five hours. The paper cylinders are then removed and dried at room temperature.

70 One further system has been used for the comparison of the various steroid products. This is known as System V. It consists of benzene saturated with water. With this system, however, untreated Whatman No. 54 filter paper sheets are used rather than the alumina impreg-

nated sheets, and cylinders of the papers are prepared of 8" x 18" sheets. Before chromatographing the products, the atmosphere of the jars is saturated with water by means of steam. The benzene saturated with water is poured in the bottom of the jar and the lid is sealed. Development is allowed to occur at room temperature until the solvent front is close to the top of the paper (three to four hours). The paper is then removed and dried at room temperature. The paper chromatography methods of Zaffaroni and of Bush, reported in the literature, are also adaptable for use here.

10

Various methods may be used to detect the various steroids on the paper chromatograms. The first of these methods entails no chemical reaction with the separated steroids and may be used before the use of either of the other methods. In this method, the sheets are examined with a fluorescent scanner as described by Haines et al., Federation Proceedings, volume 9, p. 180 (1950). The steroids having an α, β -unsaturated ketone structure and certain dienic steroids appear as dark spots when viewed through the phosphorescent screen. These may be outlined on the sheets in pencil to establish their position. Standard, known samples of the steroids may be run side by side with material prepared according to this invention. In this way it is possible to distinguish newly produced oxidized steroids. A second method for locating the steroid compounds on the paper sheets is by treatment of the sheets with a atmosphere of chlorine for 20 minutes and then spraying the sheets with a solution of 380 grams of antimony trichloride in 100 milliliters of 30 acetic anhydride. The solution is prepared fresh daily. The sprayed sheets are heated at 90-100° C. until dry and immediately examined in a dark room with a sun lamp using a Corning No. 9863 filter. Spots formed on the paper may be outlined with pencil and the relative position with respect to known samples of the various steroids may then be established.

25

An alternative method for locating certain of the steroid products is by means of the reagent described by Burton et al., J. Biol. Chem., volume 188, p. 763 (1951), which involves the spraying of the paper with an alcoholic potassium hydroxide solution of triphenyltetrazolium chloride. Steroids having a 21-hydroxy-20-keto side chain appear as red spots on drying the paper. The spots are immediately outlined in pencil since the contrast with the background soon disappears. By running paper chromatograms with a group of known oxidized steroid compounds, it has been possible to distinguish the products formed by the process of the present invention and prove the oxidation which takes place during the reaction. The various solvent systems have been used to establish, with certainty, the nature of the materials which have been formed. In conducting the paper chromatographic work, a value known as R_f has been used to identify the position of the various steroid compounds on the paper chromatograms. The R_f value for any given compound using a specific solvent system is the ratio of the distance travelled by the compound from the spot at which it was applied on the paper sheet as compared to the distance travelled by the solvent front under exactly the same conditions. The R_f value will, of course, vary with different types of compounds, with the different solvent systems, with variations in temperature, and with variations in the nature of the paper used. However, the same compound under the same set of conditions will give the same R_f and thus serve to indicate the identity of the particular product. A standard table of R_f values may be prepared for use with a given solvent system under a specific set of conditions. These values have been listed in a publication of Gilbert M. Shull et al. (Archives of 70 Biochemistry and Biophysics), vol. 37, p. 186 (1952).

The products of the new method described in this application may be isolated from aqueous solution by extraction with various water-immiscible organic solvents. Lower halogenated hydrocarbons, such as chloroform, 75

are particularly useful. After extraction, the solvent may be removed by distillation and the solid product is then isolated. This material may be further purified by recrystallization procedures from organic solvents or by chromatography, for instance on alumina columns or on other suitable solid absorbent materials. The use of a silica gel-ethanol column with a 98% to 2% by volume mixture of methylene chloride and ethanol (95%) as a developer has been found particularly advantageous. Methods for the separation of products of this nature have been reported previously in the literature. For some uses the products need not be separated, but the crude mixture may be used as such. It has been found advantageous in some cases to acylate the crude products and work with the resulting esters which are somewhat more stable.

A variety of 3-keto-4-unsaturated steroids are possible starting materials for the reactions of this invention. These include such well-known compounds as testosterone, progesterone, and Reichstein's Compound S. The oxidized products are useful as intermediates in the synthesis of other useful compounds. For example, the dehydrogenated products which contain unsaturation at the 1,2 position, along with the 3-keto group and the 4,5-unsaturation originally present in the starting material, are especially susceptible to Inhoffen aromatization. This gives rise to a group of derivatives of estrone. In the case of the dehydrogenation product of Compound S, side chain cleavage to give a 17-keto group may readily be accomplished by standard means, e.g. oxidation with chromic acid, and when the product of that reaction is aromatized by the Inhoffen reaction, e.g. heated to a high temperature in a hydrocarbon solvent, the very valuable compound estrone is produced. The introduction of oxygen functions into the nuclei of the steroids which have been oxygenated has imparted to these molecules new centers of chemical activity, and has greatly enhanced their versatility in undergoing further chemical reactions. Very desirable changes in solubility are also effected by the introduction of hydroxyl groups.

In addition to the utility mentioned above, many of the compounds produced by this reaction are extremely valuable because of their great biological activity. For example, when hydrocortisone is treated with mycobacteria according to the process of this present invention, the compound formed is prednisolone, which is of great utility and has advantages over hydrocortisone in the treatment of rheumatoid arthritis. When cortisone is treated with mycobacteria, there is produced the compound known as prednisone which also has great utility in the treatment of rheumatoid arthritis. It has also been found that other 3-keto- $\Delta^{1,4}$ steroids possess great activity as adrenocortical hormones and are useful for the same type of therapy as hydrocortisone. Many naturally occurring steroids, and steroids readily prepared from naturally occurring ones, have a 3-keto- Δ^4 structure, but no 3-keto- $\Delta^{1,4}$ compounds are readily available as raw materials. For this reason, the process of this invention whereby it is possible to transform a 3-keto- Δ^4 compound having from 18 to 21 atoms in the carbon skeleton into a 3-keto- $\Delta^{1,4}$ compound in one single step in large-scale commercial production is of tremendous value.

The following examples are given by way of illustration and are not to be considered as limitations of this invention, since as many apparently widely different embodiments of the present invention may be made without departing from the spirit and scope hereof.

A living culture of the organism employed in Examples I through IV hereinafter, namely *Mycobacterium smegmatis* (Pfizer Culture Collection No. 2), has been deposited with the American Type Culture Collection, 2029 M Street, NW., Washington, D.C., and added to its permanent collection of microorganisms as ATCC 12,549.

EXAMPLE I

A culture of *Mycobacterium smegmatis* (Pfizer Culture Collection No. 2) grown on solid agar medium, was added to 50 milliliters of nutrient solution having the following composition:

Solid, standard nutrient broth	grams/liter	8
Glycerol	mls./liter	20
Tween 80	mls./liter	0.2
Asparagine	grams/liter	5 10

The medium was sterilized before seeding. This mixture was placed in a 250-milliliter Erlenmeyer flask and the flask was shaken at about 27° C. for three days. The contents of one shake flask were used to inoculate two liters of the same sterilized medium in a 4 liter vessel equipped for conducting submerged fermentation. The medium was seeded and the mixture was stirred and aerated under sterile conditions. The stirrer was operated at a speed of 1750 r.p.m. and aeration was continued throughout 48 hours at a rate of one volume of sterile air per volume of medium per minute. The cells that had formed in the medium were centrifuged, and washed with water.

An enzyme reaction mixture was prepared containing 0.01 molar sodium fumarate, 0.01 molar magnesium sulfate, 0.03 molar sodium citrate and 0.125% adenosine triphosphate. Twenty milliliters of this medium was placed in a 125-milliliter Erlenmeyer flask. After the pH had been adjusted to 6.0 with citric acid, to the reaction mixture was added 25 milligrams of Compound S acetate. The reaction mixture was seeded with the cells from 100 milliliters of the submerged fermentation and the mixture was incubated at 37° C. Samples were removed at intervals, and the steroids present were extracted into chloroform. After separation of the organic phase, the solvent was removed and the product was dissolved in ethanol. Samples of the ethanol solution were placed on paper sheets using the chromatographic technique described above. It was found that at the end of six hours some oxidation of the nucleus of the Compound S acetate had occurred. The reaction proceeded quite rapidly and in 24 hours appreciable conversion had occurred. At the end of 48 hours, a maximum oxidation of the steroid nucleus had taken place. Paper chromatograms run using solvent System V gave the following results. The figures given in the table are R_f values and the names in parentheses are the steroid compounds to which each of the spots on the paper chromatogram conforms. These tests were made 48 hours after inoculation of the medium with cells.

 R_f Values on System V:

(Compound S acetate)	1.0
(Compound S)	0.58
(Δ^1 -dehydro-Compound S and 14 α -hydroxy-Compound S)	0.30
(Not yet identified)	0.20

EXAMPLE II

To a four liter Pyrex glass vessel equipped for conducting submerged aerated fermentation was added two liters of the following medium (known as Turfitt's medium):

	Percent
Ammonium nitrate	0.1
Dipotassium acid phosphate	0.025
Magnesium sulfate heptahydrate	0.25
Sodium chloride	0.0005
Ferrous sulfate heptahydrate	0.00001
Calcium carbonate	0.5

The aqueous medium was sterilized and then treated with 0.25 gram of Compound S acetate. The mixture was then seeded with 100 mls. of a culture of *Mycobacterium smegmatis* (Pfizer Culture Collection No. 2) grown in a shake flask on nutrient broth. The mixture

was agitated and aerated with sterile air. The whole mixture was then extracted with two liters of chloroform. Samples of this product were subjected to examination by means of paper chromatograms using three different systems. The following table indicates the R_f values of the various systems. The compounds to which these spots correspond are designated at the side of the table.

	Steroid Compounds	R _f Values—System		
		III	IV	V
15	Compound S	0.07	0.5	
	Compound S acetate			0.94
	Compound S			0.72
	Δ^1 -dehydro-Compound S and 14 α -hydroxy-Compound S			0.45

Another system of paper chromatography gave better results, especially in the separation of the Δ^1 -dehydro-Compound S and 14 α -hydroxy-Compound S, each of which had the R_f value of 0.45 when System V was employed. This other system was employed in a descending chromatograph instead of an ascending one as those previously described. The paper was impregnated with a mixture of 80 volumes of methanol and 20 volumes of water. The atmosphere in the jar was saturated with the vapor of toluene which had been saturated with water. Developing was accomplished by means of a mixture of 100 volumes of toluene and 20 volumes of ethyl alcohol. By use of this system, the following results were obtained.

 R_s values:

35	(Compound S)	1.00
	(Δ^1 -dehydro-Compound S)	0.68
	(14 α -hydroxy-Compound S)	0.45
	(Not yet identified)	0.25

These R_s values were obtained by assigning a value of 1.00 to the distance traveled by Compound S, and to each of the other compounds a value equal to the ratio of the distance traveled by that compound to the distance traveled by Compound S. Both the solvent front and Compound S acetate went over the entire length of the sheet and off the paper.

The mixture was finally separated by successive applications to silica gel-ethanol columns. When fermentation was completed, the fermentation mixture was extracted with chloroform, and evaporated to a volume of about 20 ml. This concentrated extract was then applied to a silica gel-ethanol column, and eluted with methylene chloride-alcohol mixture until most of the Δ^1 -dehydro-Compound S had been removed. The column was then eluted with methanol to remove all the remaining steroids. This procedure was repeated several times, each time starting with the extract of a fermentation conducted as described above. These methanol eluates were then combined, evaporated to dryness and dissolved in 20 ml. of chloroform. This chloroform solution was then applied to a silica gel-ethanol column and eluted with the methylene chloride-alcohol mixture.

Fractions of 50 ml. volume were collected about every two hours, and found to contain the following:

65	Fractions 1-8	(Nothing).
	Fractions 9-17	(Compound S).
	Fractions 18-19	(Δ^1 -dehydro-Compound S and 14 α -hydroxy-Compound S).
	Fractions 22-33	(14 α -hydroxy-Compound S).

The fractions were evaporated to dryness and the crystals recovered. The Δ^1 -dehydro-Compound S was twice recrystallized from ethyl acetate, and the 14 α -hydroxy-Compound S was twice recrystallized from ethyl alcohol.

Δ^1 -dehydro-Compound S, which may also be called

17 α ,21-dihydroxy- $\Delta^{1,4}$ -pregnadien-3,20-dione, has the following physical constants: M. P. 235°-236° C., optical rotation

$$[\alpha]_D^{acetone} + 71.9^\circ$$

ultraviolet absorption maximum at 245 m μ .

14 α -hydroxy-Compound S, which may also be called 14 α ,17 α ,21-trihydroxy- Δ^4 -pregnene-3,20-dione, is a white crystalline compound and has the following physical constants: M.P. 226°-228° C., and optical rotation

$$[\alpha]_D^{acetone} + 129.6^\circ$$

Analysis.—C, 69.64; H, 8.30. Calculated for C₂₁H₃₀O₅; C, 69.57; H, 8.35.

EXAMPLE III

An experiment was run exactly as outlined in the example above except that 0.25 gram of desoxycorticosterone acetate was used as the starting material. After incubation for four days at 27° C. under otherwise the same conditions the product was recovered and analyzed by means of paper chromatograms. The following table indicates the results:

Steroid Compounds	R _f Values—System			
	II	III	IV	V
Desoxycorticosterone acetate.....	0.39	0.87	1.0	.....
Desoxycorticosterone.....	.....	0.27	0.67	0.97
Δ^1 -dehydrodesoxycorticosterone.....	.....	.....	0.32	0.72
A monohydroxy nuclear substitution product of desoxycorticosterone.....	.....	.....	0.17	0.44

Again in this example the products are formed by the nuclear oxidation of the steroid starting material, one of them in each example being formed by oxygenation, and one in each example being formed by dehydrogenation at the 1,2 positions. The exact position of the hydroxyl group in the monohydroxy nuclear substitution product here obtained is not yet certainly known, except that it is in a different position from that of the nuclear hydroxyl group in corticosterone, and it is believed to be the 14 position.

EXAMPLE IV

Using the technique described above, testosterone was subjected to the action of a growing culture of a *Mycobacterium smegmatis* (Pfizer Culture Collection No. 2) in shaken flasks incubated for nine days. The product was examined by paper chromatography and there was found to be a nuclear oxygenated derivative of testosterone formed during the reaction. The compound was isolated by extraction. The exact position at which oxygen was introduced in the nucleus has not yet been determined. There was also formed another product, this one formed by dehydrogenation of the steroid nucleus at the 1,2 positions.

EXAMPLE V

Submerged, aerated fermentation using progesterone as the starting material was run with *M. smegmatis* ATCC. 278 in 4 liter fermenters for 96 hours. The products obtained were Δ^1 -dehydroprogesterone, and a product with a saturated A ring, along with some unreacted progesterone. The mixture was separated by countercurrent distribution. The physical constants for the Δ^1 -dehydroprogesterone obtained here check with those reported in the literature.

EXAMPLE VI

A culture of *Mycobacterium smegmatis* ATCC. 12,051, grown on solid agar medium was rinsed into a sterile nutrient solution having the following composition:

Solid, standard nutrient broth	grams/liter	8
Glycerol	mls./liter	20
Tween 80	mls./liter	0.2
Asparagine	grams/liter	5

One liter of this inoculated medium was placed in each of two Fernbach shake flasks. After three days, one-half gram of hydrocortisone was added to each flask. The reaction was continued for four days at the end of which time the contents of the flasks were combined and extracted 3 times, each time with an equal volume of chloroform. The combined chloroform extracts were concentrated to a volume of approximately 150 ml. A small amount of activated carbon (Nuchar) was added and the mixture was gently heated and stirred for a few minutes. The Nuchar was removed by filtration and the filtrate was put on a silica gel-ethanol chromatography column. The column was developed, using a mixture of 97% by volume ethylene chloride and 3% ethanol. 50 ml. fractions were collected. The first 37 contained no steroids. In fractions 38 through 66, unreacted hydrocortisone was recovered. Fractions 67 through 82 contained hydrocortisone and delta 1-dehydrohydrocortisone. Fractions 83 through 115 contained delta 1-dehydrohydrocortisone. Fractions 116 through 269 contained no steroid. Fractions 270 through 332 contained Δ^4 -pregnen-11 β ,17 α ,20 β ,21-tetrol-3-one.

Combined fractions 83 through 115 were evaporated to dryness on a steam bath. The residue was dissolved in 25 ethyl acetate and treated with a small amount of activated carbon. The carbon was removed by filtration, and the filtrate concentrated to a small volume and refrigerated. Crystals which formed after refrigeration were redisolved in the minimum amount of acetone. An equal 30 volume of hexane was then added, followed by the addition of cyclohexane to incipient turbidity. On additional refrigeration, white crystals formed. These have been identified as being delta 1-dehydrohydrocortisone, which may also be called prednisolone or $\Delta^{1,4}$ -pregnadien-11 β , 35 17 α ,21-triol-3,20-dione. The crystals had a melting point of 196°-198° C., a specific rotation of $[\alpha]_D^{25} + 108.2^\circ$ in ethanol and

$$\lambda_{max}^{H_2SO_4} 260, 280, 310, 358, m\mu$$

40

EXAMPLE VII

The procedure of Example VI was repeated except that cortisone was used in place of hydrocortisone. The product, Δ^1 -dehydrocortisone, which may also be called prednisone or $\Delta^{1,4}$ -pregnadien-17 α ,21-diol-3,11,20-trione, was isolated in a similar fashion.

EXAMPLE VIII

To a four liter Pyrex glass vessel equipped for conducting submerged aerated fermentation was added two 50 liters of Turfitt's medium. The aqueous medium was sterilized and then inoculated with 100 ml. of a culture of *Mycobacterium smegmatis* ATCC 12,051, grown in a shake flask on nutrient broth. After three days, 0.25 gram of hydrocortisone was added. The mixture was 55 agitated and aerated with sterile air. Four days after the addition of the steroid, the whole mixture was extracted with approximately 2 liters of chloroform. Chromatography proved the presence of Δ^1 -dehydrohydrocortisone in the product.

EXAMPLE IX

The procedure of Example VIII was repeated except that cortisone was used in place of hydrocortisone. In an identical manner, the product Δ^1 -dehydrocortisone was prepared.

EXAMPLE X

To a four liter Pyrex glass vessel equipped for conducting submerged aerated fermentation was added two 70 liters of Turfitt's medium. The aqueous medium was sterilized and then inoculated with 100 ml. of a culture of *Mycobacterium smegmatis* ATCC 12,051, grown in a shake flask on nutrient broth. After three days, 0.25 gram of 14 α -hydroxy Compound F, prepared by the method described in corresponding application Serial Number 476,-

556, filed on December 20, 1954, by G. M. Shull et al., was added. The mixture was agitated and aerated with sterile air. Four days after the addition of the steroid, the whole mixture was extracted with approximately 2 liters of chloroform. The chloroform extract was treated with activated carbon, filtered and reduced to a small volume by evaporation, and then placed on a silica gel-ethanol chromatography column. The column was eluted with mixtures of ethylene chloride and 95% ethanol, starting with mixtures containing about 2% by volume ethanol, and gradually increasing the percentage of ethanol. The compound $\Delta^{1,4}$ -pregnadien-11 β ,14 α ,17 α ,21-tetrol-3,20-dione was recovered in this fashion. The physical constants of this novel compound are as follows: M.P. 227-229° C., $[\alpha]_D^{25} +103.5^\circ$ (dioxane),

Infrared (1% in KBr pellet) most prominent absorption peaks at 2.92, 5.78, 6.03, and 9.65 microns. This compound possesses great activity as an adrenocortical hormone.

EXAMPLE XI

The procedure of Example X was repeated, except that the steroid used was 14 α -hydroxy cortisone prepared by the method described in corresponding application Serial Number 432,314, filed on May 25, 1954, by Eugene J. Agnello et al. The compound $\Delta^{1,4}$ -pregnadien-14 α ,17 α ,21-triol-3,11,20-trione was recovered by a similar method. This compound possesses great biological activity as an adrenocortical hormone.

EXAMPLE XII

Mycobacterium phlei ATCC 354 was transferred from a nutrient agar slant to a Fernbach flask containing 1000 cc. of the following medium:

Nutrient broth (Difco)	g.	8.0
Glycerol	cc.	20.0
Tween 80 (Atlas Powder Co.)	cc.	0.2
Distilled H_2O to make 1000.0 cc.		

After 2 days' shaking at 28°, 100 cc. of the resulting broth was used to inoculate each of four fermentors containing 2000 cc. of Medium CC.

	Medium CC, g.
NH_4NO_3	1.0
K_2HPO_4	0.25
$\text{MgSO}_4 \cdot 7\text{H}_2\text{O}$	0.25
NaCl	0.005
$\text{FeSO}_4 \cdot 7\text{H}_2\text{O}$	0.0001
CaCO_3	5.0
Distilled H_2O to 1000 cc.	

At the same time the fermentors were inoculated, 250 mg. of corticosterone was also added to each vessel. After 24 hours the fermentations were stopped, the broth combined and extracted with CHCl_3 . Chromatographic assay indicated conversion of the corticosterone to a slightly more polar product (Δ^1 -dehydro-corticosterone) and about 3% corticosterone remaining. Fractionation of the extract on a silica gel column provided 70 mg. of cream colored crystals melting at 217-218°, $[\alpha]_D^{25} +154^\circ$ (ethanol),

Another 8 mg. was obtained as a second crop. Comparison of this compound with corticosterone in the gluco-liver glycogen and thymus involution assays for glucocorticoids showed that the new compound was much more active than corticosterone. The compound was identified as $\Delta^{1,4}$ -pregnadiene-11 β ,21-diol-3,20-dione, the expected transformation product.

EXAMPLE XIII

Mycobacterium smegmatis ATCC 361 was transferred from a nutrient agar slant to seven Fernbach flasks each

of which contained 1000 cc. of the following medium:

	G.
Malt extract (Difco)	5.0
Dextrose hydrate	30.0
5 NaNO_3	2.0
KH_2PO_4	1.0
KCl	0.5
$\text{MgSO}_4 \cdot 7\text{H}_2\text{O}$	0.5
$\text{FeSO}_4 \cdot 7\text{H}_2\text{O}$	0.5
10 pH 6.7.	
Tap H_2O to 1000 cc.	

After 5 days shaking at 28°, 250 mg. of 14 α -hydroxy-Compound S was added to each flask. After an additional 3 days, the fermentations were stopped and the broth extracted with CHCl_3 . The combined extracts were chromatographed on silica gel to yield 33 mg. of a white crystalline product, M.P. 217-218°, $[\alpha]_D +132^\circ$ (CHCl_3),

The compound has been identified as $\Delta^{1,4}$ -pregnadiene-14 α ,17 α ,21-triol-3,20-dione.

EXAMPLE XIV

A series of experiments were run using the procedures described in the above examples, and using the following species of *Mycobacteria*, all of which are available from public culture collections:

<i>M. phlei</i> ATCC 10,142	<i>M. thamnopheos</i>
<i>M. ranae</i> ATCC 110	<i>M. lacticola</i>
<i>M. butyricum</i>	<i>M. friedmanni</i> ATCC 114
<i>M. berolinense</i> ATCC	<i>M. tuberculosis</i>

other used steroids included the following:

9 α -fluoro-Compound F	
$\Delta^{4,6}$ -androstadiendione	
11 β ,17 α -hydroxyprogesterone	
40 Δ^{14} -dehydro-Compound S	
Androstenedione	
19-nortestosterone	
17 α -hydroxyprogesterone	
16-dehydroprogesterone	
45 11-ketoprogesterone	
$\Delta^9(11)$ -dehydro-Compound S	
14 α ,15 α -epoxido-Compound S (This compound may be obtained by the method described in copending application Serial Number 459,848, filed October 1, 1954.)	
50 14 α ,15 α -epoxido-Compound F (This compound may be obtained by the method described in copending application Serial Number 432,621, filed May 26, 1954.)	

In each case the products were recovered from the reaction mixture by extraction and were subjected to evaluation by the paper chromatography method. In each case, it was found that dehydrogenation at the 1-position had occurred.

What is claimed is:

1. A process for the preparation of a 3-keto- $\Delta^{1,4}$ -steroid compound which process comprises contacting a 3-keto- Δ^4 -steroid compound having from 18 to 21 atoms in the carbon skeleton with the oxidizing enzymes of an organism of the genus *Mycobacterium*.
2. A process for the preparation of a 3-keto- $\Delta^{1,4}$ -steroid compound which process comprises subjecting a 3-keto- Δ^4 -steroid having from 18 to 21 atoms in the carbon skeleton to submerged, aerated fermentation with a living culture of an organism of the genus *Mycobacterium*.
3. A process as claimed in claim 1 wherein the organism is of the species *Mycobacterium phlei*.
4. A process as claimed in claim 1 wherein the organism is of the species *Mycobacterium smegmatis*.
5. A process as claimed in claim 2 wherein the organism is of the species *Mycobacterium phlei*.

6. A process as claimed in claim 2 wherein the organism is of the species *Mycobacterium smegmatis*.

7. A process for the preparation of $\Delta^{1,4}$ -pregnadien-11 β ,17 α ,21-triol-3,20-dione which process comprises contacting Δ^4 -pregnene-11 β ,17 α ,2-triol-3,20-dione with the oxidizing enzymes of an organism of the genus Mycobacterium.

8. A process for the preparation of $\Delta^{1,4}$ -pregnadien-17 α ,21-diol-3,11,20-trione which process comprises contacting Δ^4 -pregnene-17 α ,21-diol-3,11,20-trione with the oxidizing enzymes of an organism of the genus Mycobacterium.

9. A process for the preparation of $\Delta^{1,4}$ -pregnadien-17 α ,21-diol-3,20-dione which process comprises contacting Δ^4 -pregnene-17 α ,21-diol-3,20-dione with the oxidizing enzymes of an organism of the genus Mycobacterium.

10. A process for the preparation of $\Delta^{1,4}$ -pregnadien-11 β ,14 α ,17 α ,21-tetrol-3,20-dione which process comprises contacting Δ^4 -pregnene-11 β ,14 α ,17 α ,21-tetrol-3,20-dione with the oxidizing enzymes of an organism of the genus Mycobacterium.

10

15

20

11. A process for the preparation of $\Delta^{1,4}$ -pregnadien-14 α ,17 α ,21-triol-3,11,20-trione which process comprises contacting Δ^4 -pregnene-14 α ,17 α ,21-triol-3,11,20-trione with the oxidizing enzymes of an organism of the genus Mycobacterium.

12. A process for the preparation of $\Delta^{1,4}$ -pregnadien-11 β ,17 α ,21-triol-3,20-dione which process comprises contacting Δ^4 -pregnene-11 β ,17 α ,21-triol-3,20-dione with the oxidizing enzymes of *Mycobacterium phlei*.
